UNITED STATES PATENT OFFICE.

WILLIAM M. SULETTE, OF LOS ANGELES, CALIFORNIA, ASSIGNOR OF ONE-HALF TO
CHAUNCEY M. BLAIR, OF LOS ANGELES, CALIFORNIA.

GASIFIER.

1,397,063.

Specification of Letters Patent. Patented Nov. 15, 1921.

Application filed September 2, 1920. Serial No. 407,704.

To all whom it may concern:

Be it known that I, WILLIAM M. SULETTE, a citizen of the United States, residing at Los Angeles, in the county of Los Angeles and State of California, have invented certain new and useful Improvements in a Gasifier, of which the following is a specification.

The objects of this invention are, first,—to construct a gasifier that can be used in connection with any carbureter and any ignition system of an internal combustion engine; second,—to economize the consumption of gasolene or similar fuels under any climatic conditions; third,—to assist carburetion when the engine is cold, by a preheating process; fourth,—to construct a gasifier that is simple, easy to manufacture, and automatic in operation.

With the foregoing and other objects in view which will appear as the description proceeds, my invention resides in the combination of details and construction herein-after described and claimed.

I attain these objects by the illustration in the accompanying drawing, in which:

Figure 1 represents a part plan, and a part section on line B—B of Fig. 2.

Fig. 2 represents a section on line A—A of Fig. 1.

Referring to the drawings in which like characters of reference designate similar parts, 1 represents the housing, the connection 19 is integral with the top portion thereof, and the connection 20 is integral with the bottom portion thereof, the combustion chamber 2 is circularly positioned around the inner side of the said housing 1, the intake tube 3 passes through the connection 20 into the center of the housing 1, the valve chamber 4 is in turn adapted to lead from the said intake tube 3 to the connection 19, the delivery chamber 15 is circularly positioned around the intake tube 3 and the lower-inner portion of the combustion chamber 2, the port hole 14 is adapted to pass from the intake tube 3 to the said delivery chamber 15, the delivery hole 12 is in turn adapted to pass from the delivery chamber 15 to the combustion chamber 2, and the screen 13 is positioned in the said delivery hole 12. A plurality of exhaust tubes 10 are adapted to pass from the combustion chamber 2 to the valve chamber 4, and the screens 11 are in turn positioned in

the said exhaust tubes 10. The valve 5 is seated in the junction of the said intake tube 3 and the valve chamber 4, a valve stem 17 is integral with the center portion of the valve 5, the spider 7 is seated in the said connection 19 and is adapted to operatively receive the said valve stem 17, the spring 8 is positioned between the said valve 5 and the spider 7, the slide 6 is operatively positioned in the intake tube 3 and is adjustably mounted on the said valve stem 17 by the nut 18. A spark plug 9 is adapted to pass through the housing 1 to the said combustion chamber 2, and is adapted to connect in circuit with an ignition system, not shown, the connection 19 is secured to a manifold of an internal combustion engine, not shown, and the connection 20 is in turn secured to a carbureter, not shown.

With the operation of my gasifier, the engine is first set into motion to draw vapor from carbureter, past the slide 6 into intake tube 3, the vapor is then adapted to lift the valve 5 in proportion to the suction developed by the said engine, against the tension of the spring 8, a predetermined amount of vapor is thus admitted from the said intake tube 3 through the valve 5 into the valve chamber 4. A portion of the vapor admitted into the said intake tube 3 passes through the port hole 14, into the delivery chamber 15, through the delivery hole 12, and screen 13 respectively, into the combustion chamber 2, spark plug 9 is connected to the ignition system to ignite the vapor within the said combustion chamber 2, the burnt gases are discharged through the exhaust tubes 10, and the screen 11, into the said valve chamber 4, and is then assimilated by the said vapor in the valve chamber 4, the said vapor is thus preheated by the said hot burnt gases to assist combustion when delivered to the said engine. The delivery chamber 15 with the screen 13, and the exhaust tubes 10 with the screens 11, are adapted to prevent the flame caused by the burning vapor in the combustion chamber 2 from spreading into the intake tube 3, or the valve chamber 4.

As the engine increases its velocity and draws an increased flow of vapor, valve 5 is adapted to be lifted into a more open position, and the slide 6 is adapted to be closed thereby over the port hole 14, in proportion to the predetermined adjustment of the nut

18 on the valve stem 17, and when a full flow of vapor is attained the valve 5 is in like manner held into its open position, and the slide 6 is closed therewith to cut off the 5 supply of vapor to the combustion chamber 2 and the preheating process of my gasifier is thus discontinued.

While in the specification a preferred construction is set forth in detail, still in 10 practice such deviations from such detail may be resorted to as do not form a departure from the spirit of my invention.

Having thus described this invention, what is claimed is:

15 In a gasifier of the class described, adapted to be connected between the carbureter and the intake manifold of an internal combustion engine, the combination of a combustion chamber with a firing means; an intake tube passing from the carbureter through

said combustion chamber; a valve chamber connecting said intake tube with said manifold; a delivery chamber circularly positioned between the said intake tube and the combustion chamber, adapted to admit vapor from the said intake tube to the combustion chamber; an exhaust means leading from the said combustion chamber to the valve chamber, adapted to prevent the passage of fire therethrough; a valve means positioned within the said valve chamber, adapted to automatically open and close with the volume of gas vapor sucked therethrough; a slide operatively positioned within the said intake tube, adapted to alternately close and 30 open the port hole to the said delivery chamber with the action of the said valve means as set forth.

In testimony whereof I affix my signature.

WILLIAM M. SUBLETTE.
